[57] CLAIM

The ornamental design for a rotatable toy kite, substantially as shown and described.

DESCRIPTION

FIG. 1 is a perspective view of a rotatable toy kite showing my new design;
FIG. 2 is a side elevational view thereof;
FIG. 3 is a top plan view thereof; and,
FIG. 4 is a rear elevational view thereof looking from the left of the side elevational view of FIG. 2.

Fig. 3.

Fig. 4.
